UNITED STATES PATENT OFFICE

HERMANN RUETER, OF NIAGARA FALLS, NEW YORK, ASSIGNOR OF ONE-HALF TO
DRAGUTIN HERL, OF NIAGARA FALLS, NEW YORK

RAILWAY CHAIR

Application filed September 5, 1929. Serial No. 390,537.

This invention relates to certain new and useful improvements in railway chairs.

The primary object of the invention is to provide a railway chair upon which the meeting ends of rails are seated and retained therein in the absence of the usual fastening bolts, fish plates, spikes and the like, the chair comprising parts cooperating with the rail ends to provide an interlocking connection for the retention of the rail ends and being of a nature to permit slight longitudinal expansion and contraction thereof which is necessary in the laying of rails.

With the above and other objects in view that will become apparent as the nature of the invention is better understood, the same consists in the novel form, combination and arrangement of parts hereinafter more fully described, shown in the accompanying drawings and claimed.

In the drawing:—

Figure 1 is a fragmentary top plan view showing the meeting ends of rails seated in the improved railway chair that is mounted at its ends upon cross ties;

Figure 2 is a fragmentary side elevational view of the rail ends in position in the railway chair, showing the rail ends anchored in the chair without the provision of nails or spikes;

Figure 3 is a horizontal longitudinal sectional view showing the meeting rail ends seated in the railway chair and locked in by spring ends carried by the railway chair and engaged with the rail ends;

Figure 4 is a top plan view of the railway chair seated upon ties; and

Figure 5 is a fragmentary side elevational view of the seating ends of the rails showing the keeper sockets in the portions thereof for the spring catches on the railway chair.

Referring more in detail to the accompanying drawing, the reference numeral 1 designates cross-ties upon which the railway chairs are seated to receive meeting rail ends, the railway chair comprising end portions 2 mounted upon the ties 1 and connected by an intermediate portion 3 of increased thickness and depending below the upper sides of the cross ties for strengthening the chair, the

end portions 2 being anchored to the cross ties by spikes 4. The chair includes a bottom wall for the support of the meeting ends of the rails 6 and has side walls 7 and 8 having the usual curvature, angles and bends for intimate contact with the base flanges and webs of the rail ends as illustrated. The side wall 7 of the chair at the central portion 3 extends upwardly into contact with the adjacent sides of the rail treads, while the end portions thereof are of lesser height as indicated at 9.

The opposite side wall 8 of the railway chair has the central portion thereof extended upwardly into engagement with the treads of the meeting rail ends, while the outer ends of the side wall 8 taper downwardly with the lower sides thereof cut away from the end portions 2 of the chair to provide spring arms 10 shown more clearly in Figure 2. Each spring arm 10 carries upon its inner side at the outer end, a latch lug 11 and locking shoulder 12 disposed inwardly of the end of the spring arm 10 with a cam or inclined face 13 extending to the end of the spring arm.

The adjacent side of the web of each rail end is provided with a locking socket to receive the latch lug 11 and is formed by a tapering bottom wall 14 ending at a transverse abutment shoulder 15 adjacent the rear end.

The railway chair is first mounted upon the crossties 1 and anchored thereto by the bolts or spikes 4. The rail ends 6 are then slid into the open opposite ends of the chair with the keeper sockets 14 in the webs of the rails facing the side wall 8 of the chair. The ends of the rails first engage the latch lugs 11 and move them outwardly against inherent spring tension thereof to cause them to ride over the adjacent face of the rail web until the keeper sockets register with the latch lug and at which time the latter will spring into the keeper sockets for anchoring the rail end in position. The keeper sockets and latch lugs may be so located with respect to the rail ends as to permit limited expansion and contraction of the rail ends while securely retaining the rail ends anchored in the chair. To remove the rail ends for purposes of repair

or replacement, a tool or the like is engaged with the outer end of the latch lug 11 as will be evident from an inspection of Figure 3 to move the arms 10 outwardly for displacing the latch lug from the keeper socket 14 and at which time the rail may be longitudinally shifted and disengaged from the chair.

From the above detailed description of the invention, it is believed that the construction and operation thereof will at once be apparent, and while there is herein shown and described the preferred embodiment of the invention, it is nevertheless to be understood that minor changes may be made therein without departing from the spirit and scope 15 of the invention as claimed.

I claim:—

1. In a device of the character described, a railway chair, meeting rail ends seated therein and an interlocking connection between the chair and rail ends, including spring arms formed integral with the ends of the chair and having end latch lugs and cooperating locking sockets in the rail ends.

2. In a device of the character described a railway chair, meeting rail ends seated therein and an interlocking connection between the chair and rail ends, including spring arms formed integral with the chair and having end latch lugs and each rail end having a locking socket therein to receive the adjacent latch lug.

3. In a device of the character described, a railway chair, meeting rail ends seated therein and an interlocking connection between the chair and rail ends, the chair including side walls engaging the rail ends, a longitudinally extending spring arm on each end of a side wall, each arm having an end latch lug, and the rail ends having locking sockets to receive the latch lugs.

4. In a device of the character described, a railway chair, meeting rail ends seated therein and an interlocking connection between the chair and rail ends, the chair including side walls engaging the rail ends, a pair of outwardly directed spring arms formed on one of the side walls, a latch lug on the free end of each spring arm, and the rail ends having locking sockets to receive the latch lugs.

In testimony whereof I affix my signature.
HERMANN RUETER.
